(57) **CLAIM**

The ornamental design for a freeze dryer tray lid, as shown and described.

DESCRIPTION

FIG. 1 is a top right isometric view of a freeze dryer tray lid; FIG. 2 is a top right isometric view of a freeze dryer tray lid; FIG. 3 is a bottom left isometric view of a freeze dryer tray lid;

FIG. 4 is a top plan view of a freeze dryer tray lid; FIG. 5 is a bottom plan view of a freeze dryer tray lid; FIG. 6 is a front elevation view of a freeze dryer tray lid; FIG. 7 is a sectional view of FIG. 4 depicting a rear elevation view of a freeze dryer tray lid;

FIG. 8 is a right elevation view of a freeze dryer tray lid; FIG. 9 is a sectional view of FIG. 4 depicting a left elevation view of a freeze dryer tray lid;

FIG. 10 is a detailed view of FIG. 1 of a freeze dryer tray lid; FIG. 11 is a detailed view of FIG. 2 of a freeze dryer tray lid; FIG. 12 is a detailed view of FIG. 3 of a freeze dryer tray lid; FIG. 13 is a detailed view of FIG. 4 of a freeze dryer tray lid; FIG. 14 is a detailed view of FIG. 5 of a freeze dryer tray lid; FIG. 15 is a detailed view of FIG. 6 of a freeze dryer tray lid; FIG. 16 is a detailed view of FIG. 7 of a freeze dryer tray lid; FIG. 17 is a detailed view of FIG. 8 of a freeze dryer tray lid; and,

FIG. 18 is a detailed view of FIG. 9 of a freeze dryer tray lid. A description of the appearance of the article is as follows: The broken lines showing portions in all figures is included for the purpose of illustrating unclaimed environment and unclaimed features and forms not part of the claimed design.
